(57) **CLAIM**

The ornamental design for a tire, as shown and described.

DESCRIPTION

FIG. 1 is a perspective view of a tire showing my new design; FIG. 2 is a front view thereof, for which the rear view is the same;

FIG. 3 is a top plan view thereof, for which the bottom plan view is the same;

FIG. 4 is a right side view thereof, for which the left side view is the same;

FIG. 5 is an enlarged view taken along line 5-5 in FIG. 1;

FIG. 6 is an enlarged view taken along line 6-6 in FIG. 2;

FIG. 7 is an enlarged view taken along line 7-7 in FIG. 2;

FIG. 8 is an enlarged view taken along line 8-8 in FIG. 6;

FIG. 9 is an enlarged view taken along lines 9-9 and 9'-9' in FIG. 7;

FIG. 10 is an enlarged cross-sectional view taken along lines 10-10 in FIG. 4 and 10'-10' in FIG. 7; and,

FIG. 11 is an enlarged cross-sectional view taken along lines 10-10 in FIG. 4 and 11-11 in FIG. 7.

In the drawings, the broken lines defining portions of the sidewall and inner bead depict environmental subject matter that forms no part of the claimed design.

(57) **CLAIM**

The ornamental design for a tire, as shown and described.

DESCRIPTION

FIG. 1 is a perspective view of a tire showing my new design; FIG. 2 is a front view thereof, for which the rear view is the same;

FIG. 3 is a top plan view thereof, for which the bottom plan view is the same;

FIG. 4 is a right side view thereof, for which the left side view is the same;

FIG. 5 is an enlarged view taken along line 5-5 in FIG. 1;

FIG. 6 is an enlarged view taken along line 6-6 in FIG. 2;

FIG. 7 is an enlarged view taken along line 7-7 in FIG. 2;

FIG. 8 is an enlarged view taken along line 8-8 in FIG. 6;

FIG. 9 is an enlarged view taken along lines 9-9 and 9'-9' in FIG. 7;

FIG. 10 is an enlarged cross-sectional view taken along lines 10-10 in FIG. 4 and 10'-10' in FIG. 7; and,

FIG. 11 is an enlarged cross-sectional view taken along lines 10-10 in FIG. 4 and 11-11 in FIG. 7.

In the drawings, the broken lines defining portions of the sidewall and inner bead depict environmental subject matter that forms no part of the claimed design.
